CLAIM

The ornamental design for an adhesive patch as shown and described.

DESCRIPTION

FIG. 1 is a front elevation view of an adhesive patch showing our new design;

FIG. 2 is a back elevation view thereof;

FIG. 3 is a top view thereof;

FIG. 4 is a bottom view thereof;

FIG. 5 is a right side view thereof; the left side view being a mirror image thereof; and,

(Continued)

FIG. 6 is an cross sectional view of FIG. 2 taken along lines 6-6.

The dash-dash broken lines depict portions of the adhesive patch that form no part of the claimed design. The dot-dash broken lines depict a boundary of the claimed design and form no part thereof.

1 Claim, 3 Drawing Sheets
